PERMANENT WAVE APPARATUS

Filed April 15, 1935

UNITED STATES PATENT OFFICE

2,086,636

PERMANENT WAVE APPARATUS

Gust W. Peterson, Long Beach, Calif.

Application April 15, 1935, Serial No. 16,493

6 Claims. (Cl. 132—36)

This invention relates to permanent wave apparatus, and has for an object the provision of means for more effectively retaining the essential heat and hot gases about the strand of hair under treatment than was possible with the devices of the prior art and enabling a higher degree of permanency to be given the wave.

A further object is to provide apparatus embodying a novel form of sealing means adapted to be conveniently placed about the curling spindle of the heater and effectively sealed against surfaces of the hair clamp in a manner to prevent the hot vapors in the spindle chamber of the heater from discharging against the scalp.

Another object is to provide a novel and exceedingly effective form of heater consisting of few complementary parts, the forms, constructions and arrangements of which are such that they can be very readily assembled and connected together and fulcrum on each other in a manner to allow for the formation of an opening of maximum proportion at one side of the heater for quick and convenient application of the spindle to and removal of same from the heating chamber.

Another object of the invention is to provide apparatus of the class described, the co-operable parts of which are designed, constructed and arranged to prevent contact with the scalp of hot metallic surfaces when the apparatus is applied to the head, thus preventing burning of the scalp and affording considerably more comfort to the user than was heretofore possible.

With the above and other objects in view, the invention consists in the novel construction and combination of parts hereinafter described, illustrated in the accompanying drawing, set forth in the claims hereto appended, it being understood that various changes in the form, proportion, size and minor details of construction within the scope of the claims may be resorted to without departing from the spirit or sacrificing any of the advantages of the invention.

In the drawing:

Figure 1 is a view in front elevation of the complete apparatus;

Figure 2 is a view in end elevation thereof;

Figure 3 is a view in elevation looking toward the clamp side of the apparatus;

Figure 4 is a section taken on the line 4—4 of Figure 1;

Figure 5 is a perspective view of the complementary gripping elements of the jaws of the clamp;

Figure 6 is a perspective view of one of the jaws of the heater; and

Figure 7 is a perspective view of the other jaw of the heater.

In carrying the invention into practice, use is made of a heater 10 and a coacting clamp 11.

The heater 10 comprises complementary jaws 12 and 13, the former consisting of a single blank of stiff metal upstruck to provide a substantially ovate hollow structure 14 in which is mounted 10 an electrically heated coil 15 of any well known construction, and continuing from said structure is a semi-cylindrical portion 16, the ends of which are provided with semi-circular flanges 17. At one side, the structure 14 is formed with a linear 15 groove 18, the purpose of which will appear presently. To complete the formation of the jaw 12, use is made of a metallic stiffening strip 19 riveted or otherwise suitably secured at 20 to the opposite side of the structure 14 and terminating at one end in an angular flange 21 between which and the external surface of the portion 16 is firmly secured a flat strip of hard rubber or like material 22, the same extending from one end of the semi-cylindrical portion 16 of the jaw to the 25 other end thereof. At the center, the aforementioned stiffening strip 19 is formed with a diagonally disposed lug 23 to which one end of a non-metallic handle 24 of heat insulating material is secured. Said stiffening strip is formed with 30 longitudinally aligned elongated depressions 25.

The jaw 13 is similar in form to the jaw 12 and same consists of a single blank of stiff metal formed with a semi-cylindrical portion 26, the latter upstruck to provide semi-circular end 35 flanges 27 which confront the flanges 17 of jaw 16. In back of the structure formed as just de-

scribed is a stiffening strip of metal 27a which is formed with aligned linear depressions 28. The central portion of said strip is formed with a diagonally disposed lug 29 to which one end of a handle 30 of heat insulating material is secured. The strip 27a is provided with an angular flange 31, between which and the external surface of portion 26 is secured a strip of hard rubber or 45 similar material 32. The flanges 27 are continued into the upper ring portions 27b of the blank from which the jaw is formed and same are adapted to freely lap over the ends of the complementary jaw 12 as shown in Figure 2, whereby 50 to secure both jaws against relative longitudinal movement. Above said ring portions, the body of the blank is formed with a linear flange 33 which is freely received in the groove 18 of jaw 12, whereby the jaws may be hinged together to en- 55

able them to be opened and closed as and when desired. The two jaws 12 and 13 are resiliently held closed against each other by stiff loop springs 35 of flat steel, the respective free ends of which are received in the depressions 25 and 28 of the respective jaws.

A heater constructed as aforementioned is thus provided with a heating chamber 36 which is defined by the semi-cylindrical portions 16 and 26 of the respective jaws 12 and 13, and said chamber is adapted to receive and completely enclose a spindle 37 on which a strand of hair is adapted to be wound as is customary and well known in the art.

15 The aforementioned heater of the invention is used in combination with the hair clamp 11, the same comprising the co-operable jaws 38 and 39. These jaws are each formed of narrow parallel strips of heat insulating material 40—40 secured to the opposite sides of a metallic insert 41. At one end of the clamp, the metallic inserts 41 are connected together by hinge strips 42, in which one thereof is provided with a bearing bracket 43 to rotatably receive the end of the spindle 37 which carries the usual ratchet wheel 44 with which the detent spring 45 is adapted to engage and thereby hold the spindle against unwinding. The opposite ends of the jaws are connected together by a latching link 46, the same having a cam 47 which coacts with the jaw 39 to secure the clamp in applied position against the hair close to the scalp.

1 The opposite end of the spindle 37 is rotatably received in the bearing bracket 48 on link 46. 35 Firmly secured between the stiff insulating materials 40 of the jaws 38 and 39 are soft rubber strips 49 between which the hair at the scalp is adapted to be resiliently gripped. These strips are formed with parallel linear flanges 50 which are sufficiently offset from the inner face of the clamp to afford a yielding surface for direct contact with the scalp rather than allow any of the metal parts to contact the scalp. At the opposite side of the clamp, the strips 49 are formed with 45 relatively wide flanges 51 between which the hair may be clamped and against the external surfaces of which pressure may be brought to bear by virtue of the hard rubber strips 22 and 32 of the respective jaws 12 and 13 when the device is 50 fully adjusted to the position shown in Figure 4.

In order to prevent the hot vapors escaping from the chamber 36 during the process of waving the hair, use is made of a sealing strip of soft absorbent material 52, one side of which is 55 faced with an impervious sheet 53, such as waterproof paper, the size of which is the same as that of strip 52. The material 52 may be cotton or any other material which is soft and capable of yielding when pressure is brought thereagainst.

60 In operation, the hair is wound upon the spindle 37 in a manner well known to those trained in the art to which the invention relates, it being understood that the clamp 11 is firmly secured to the hair and that the flanges 50 are in 65 yielding engagement with the scalp. After the hair has been tightly wound onto the spindle and the latter held against retrograde rotation in the bearings 43 and 48, the aforementioned sealing strip is then passed around the spindle and its 70 free ends brought into overlapping relation to the external faces of flanges 51, the soft pliable material of the strip being disposed inwardly. The jaws 12 and 13 of the heater 10 are then applied as shown in Figure 4, whereby the hard rubber strips 22 and 32 will bear firmly against the outer

impervious sheet 53, the soft inner strip 52 being yieldingly pressed tightly against said external surfaces of flanges 51, whereby to prevent the escape of hot vapors from between the co-operable jaws of the heater.

5 The spindle 37 is of the perforated type to enable the hot vapors to pass into the outlet bore 54 of the spindle. It follows from what has been stated that the hot vapors are maintained against escaping from the chamber except by way of the bore 54, and that in consequence thereof the heat will be more effectively utilized than was possible with the devices of the prior art and that the clamp 11 cannot only be more comfortably worn upon the head during treatment of the hair, but 15 that the scalp will be protected against being accidentally burned either by the hot gases or the hot metallic parts of the clamp.

What I claim as my invention is:

1. The combination with a heater comprising a 20 pair of members defining a chamber for a curling spindle, and means for pressing said members toward each other to enclose the spindle in the chamber; of a hair clamp, and a sealing element removable from the chamber and adapted to embrace the spindle and having terminal portions engaged by the members and maintained thereby in gripping engagement with those portions of the clamp between which the hair strand under treatment is interposed, whereby to prevent escape of hot vapors from between said members at said clamp.

2. A device of the class described comprising a clamp having laterally projecting confronting portions of soft pliable material between which a 35 strand of hair can be clamped; and a heating chamber for receiving a spindle on which hair to be waved can be wound and said chamber including portions in removable gripping engagement with said confronting portions of the clamp 40 to prevent lateral escape of hot vapors from the chamber at the clamp.

3. A device of the class described comprising a clamp having laterally projecting confronting portions between which a strand of hair can be 45 clamped; and a heating chamber for receiving a spindle on which hair to be waved can be wound and said chamber including portions between which said laterally confronting portions of the clamp are adapted to be interposed and gripped 50 by said heating chamber portions so as to prevent lateral escape of hot vapors from the chamber at the clamp.

4. A heater comprising a jaw having a substantially ovate portion for reception of a heat- 55 ing element and said portion having a linear groove at one side and said jaw being also formed with a semi-cylindrical chamber defining portions, a jaw having a semi-cylindrical chamber defining portion confronting the chamber defin- 60 ing portion of the first named jaw and having a flange extending into said groove to enable one jaw to tilt relative to the other; and spring means engaging the jaws to press same together to house a spindle within said chamber defining por- 65 tions.

5. A heater comprising a jaw having a sub- 70 stantially ovate portion for reception of a heat- ing element and said portion having a linear groove at one side and said jaw being also formed with a semi-cylindrical chamber defining portion, a jaw having a semi-cylindrical chamber defin- 75 ing portion confronting the chamber defining portion of the first named jaw and having a flange extending into said groove to enable one 75

- 5 jaw to tilt relative to the other; spring means engaging the jaws to press same together to house a spindle within said chamber defining portions; and each jaw including a plate having recesses receiving the ends of said springs and provided with flanges exteriorly related to said chamber defining portions; and linear strips of stiff material secured between said chamber defining portions and said flanges for gripping engagement with a hair clamp.
- 10 6. The combination, with a hair clamp having longitudinally extending yieldable jaws between the inner faces of which hair can be clamped,
- of a heating chamber having longitudinally extending jaws adapted to engage the outer faces of the jaws of said hair clamp; and means of moisture-proof sheet material removably received in the chamber and within which a hair-coiling 5 spindle can be enclosed and including longitudinal portions extending axially of the spindle and disposed exteriorly of the chamber so as to be confined by the jaws of the latter in fluid sealed engagement with the outer faces of the yieldable 10 jaws of said hair clamp.
